M. A. WALDEN,
MUSIC LEAF TURNER,
APPLICATION FILED MAR. 30, 1920.

1,384,364.

Patented July 12, 1921.

FIG. 1

UNITED STATES PATENT OFFICE.

MARCUS A. WALDEN, OF SAN FRANCISCO, CALIFORNIA.

MUSIC-LEAF TURNER.

1,384,364.

Specification of Letters Patent. Patented July 12, 1921.

Application filed March 30, 1920. Serial No. 369,993.

To all whom it may concern:

Be it known that I, MARCUS A. WALDEN, a citizen of the United States, residing at San Francisco, in the county of San Francisco and State of California, have invented new and useful Improvements in Music-Leaf Turners, of which the following is a specification.

This invention relates to improvements 10 in a device for mechanically turning the leaves of sheet music.

The primary object of this invention is to provide exceptionally simple, inexpensive, and compact mechanism with which the 15 leaves of sheet music may be easily and accurately turned by the simple action of pressing a button or similar device located within easy reach of the operator.

The invention possesses other advantages 20 and features, some of which, with the foregoing, will be set forth at length in the following description wherein I shall outline in full that form of the invention which I have selected for illustration in the drawings accompanying and forming a part of 25 the present specification. In said drawings, I have shown one form of the construction of my invention, but it is to be understood that I do not limit myself to such form, since 30 the invention as expressed in the claims may be embodied in a plurality of forms.

Figure 1 is a front elevation of the music leaf turner of this invention showing in dotted lines a book of sheet music in position 35 it would appear when ready to have the leaves thereof turned.

Fig. 2 is a fragmentary bottom plan view of the mechanism of this invention.

Fig. 3 is a fragmentary side elevation of 40 the mechanism, a part being broken away and shown in section.

Fig. 4 is a fragmentary plan view partly in section of a modified form of turning mechanism.

Fig. 5 is a side elevation of another modified form of the invention.

Fig. 6 is a similar view taken on line 6—6 of Fig. 1.

The present embodiment of this invention 50 comprises a base board or plate 1 which is adapted to support sheet music 1, and may be mounted upon a suitable standard not shown or placed upon the music rack of a piano. Secured to the lower edge of this 55 base is mechanism supporting plate 2, the upper edge of which acts as a support for

the lower edge of the music mounted upon the base 1.

A plurality of concentric tubular shafts 3, 4, and 5, respectively, arranged one within 60 the other, are mounted vertically upon the base 2 in a bearing tube 6 suitably fixed to the base, the shaft 3 being journaled at its lower end in a suitable bearing 7 which latter is fixed, as at 8, to the plate 2. 65

Fixed adjacent to the lower ends of the shafts 3, 4, and 5, are fingers 9, 10, and 11, extending at right angles to said shafts and over said plate 2. The outer ends of these fingers are bent upwardly and right angularly to provide leaf engaging portions 12 70 equidistantly spaced from one another and adapted to engage under the leaves of the music to be turned. The portions 12 project outwardly from the inner edge of the 75 plate 2 and when several pages of sheet music or a book or a single page, are supported upon the base 1, the page or pages are mounted over said portions 12, so that by rotating the shafts 3, 4 and 5, the fingers 80 will be moved and the pages correspondingly turned.

As a means for rotating the shafts 3, 4, and 5, selectively, I provide a plurality of 85 slots or openings 13 formed through the plate 2 and base 1 and under the points at which the fingers 9, 10, and 11 are secured to their respective shafts. Pivotedly mounted, as at 14, within the openings 13 are rocking members 15 provided with upwardly and 90 inwardly curved arms 16 adapted at their ends to engage the fingers 9, 10, and 11. The free ends of these arms are split and the split portions 17 are directed angularly 95 in opposite directions so as to provide a relatively wide engaging surface for the fingers 9, 10 and 11. By rocking these members 15 in one direction, certain ends thereof will engage the fingers 9, 10, and 11, and move said fingers through approximately 180°. 100 In this connection, it will be noted that the fingers 9, 10, 11 lie in superposed parallel relation to the plate 2, this being provided for by lugs 17 on the portions 12, said lugs depending from the fingers and normally 105 resting upon the plate 2.

To operate the rocking members 15, I provide flexible elements 18 and 19 respectively which are connected, as at 20, to the member 15 on opposite sides of the pivot 14. 110 These flexible elements 18 and 19 cross one another under a friction roller 21 suitably

supported in bearings 22 on the under side of the base 1 and said elements are then extended toward the outer edges of the base and under similar friction rollers 23. Pivotally mounted intermediate of their ends in suitable supports 24 upon the plate 1 are a plurality of levers 25, on certain ends of which are secured suitable buttons 26 whereas the other ends are connected, as at 27, 10 with the flexible elements 18 and 19. These elements are extended upwardly through the openings 27' in the base 1 and plate 2. There are provided upon each side of the rocking members 15 a number of levers 25 responding to the number of shafts and 15 turning fingers.

In the operation of the turning device, assuming that several pages of music have been mounted upon the base 1, the leaf engaging portions 12 are inserted successively under the successive pages to be turned. To turn the first page, the the lowermost lever 25 on one side is depressed at the button end 26 thereof. In this connection, it is to be noted that the levers 25 are arranged in 25 staggered relation, the ones nearest the operator being for the shaft 3 and the one next nearest for the shaft 4, and so on. With this arrangement, it is possible to arrange the 30 fingers under the pages to be turned so that operation of the fingers may be carried on without confusion. Assuming that the lowermost right hand lever is depressed, the flexible element will be pulled, so as to rock the member 15 which operates the fingers 11. The member 15 will thus rock from left to right and the right hand end of the arm 16 will engage the finger 11 and lift said finger, moving it with the page in contact 40 therewith, through an arc of 180°, so that the page is completely turned. This movement is permitted since the other flexible element 19 will be pulled and will rock the lever on the other side of the device connected 45 thereto, to give sufficient slack to permit of the rocking of the member 15. It will thus be seen that by pressing any of the buttons 26, and rocking the levers 25, the leaves of 50 the book or sheet music may be turned, as desired. It is apparent that the device may be operated to turn from right to left or from left to right.

I may provide a plurality of page gripping members 29, 30, and 31 in the form

of spring clasps. These clasps are carried 55 on the outer ends of arms 32 which are fixed by suitable collars 33 to the ends of shafts 3, 4, and 5. The clasps may be used independently of the turning fingers or in conjunction therewith to turn the pages of the 60 music. This form is particularly illustrated in Fig. 4 of the drawings.

In Fig. 5 of the drawings I have shown a modified form of page clasping device which 65 comprises a spring clasp 34 fixed to the outer end of an arm 35, the latter being provided with a right angularly disposed inner terminal 36 adapted to engage in one of the tubular concentric shafts preferably the shaft 3. This form of the invention, is particularly adapted to turn single sheets of 70 music and may be readily adapted to the preferred form of the invention to operate in conjunction therewith.

I claim:—

1. A music leaf turner, comprising a base 75 for supporting sheet music, a plurality of concentric shafts mounted on said base, turning members fixed to the shafts, and adapted to engage sheets of music, and means for rotating said shafts to move said turning members and turn the sheets of music, said means comprising rocking members pivoted intermediate of their ends to the base and adapted at their ends to engage said turning 80 members, crossed flexible elements secured to the rocking members on opposite sides of the pivot thereof, and levers pivotally mounted intermediate of their ends upon the base and connected with said flexible elements.

2. A music leaf turner, comprising a base 85 adapted to support sheet music, a plurality of concentric rotary shafts mounted upon said base, a plurality of turning members 90 secured to said shafts, and having their terminal portions disposed beneath the sheets to be turned, a plurality of rocking members mounted on said base and having their terminal portions adapted to engage said 95 terminals when said members are rocked, a plurality of levers pivoted intermediate of their lengths on opposite sides of said shafts, flexible elements connected with certain ends 100 of said levers, crossed and secured at their other ends to said rocking members on opposite sides of said rocking members.

MARCUS A. WALDEN.
